UNITED STATES PATENT OFFICE.

ERVIN J. KRUCK AND WALTER A. KRUCK, OF NEW YORK, N. Y.

CONTROLLING DEVICE FOR MECHANICAL MUSICAL INSTRUMENTS.

1,175,531.

Specification of Letters Patent.

Patented Mar. 14, 1916.

Application filed March 30, 1915. Serial No. 17,986.

To all whom it may concern:

Be it known that we, ERVIN J. KRUCK and WALTER A. KRUCK, citizens of the United States, residing in the borough of Brooklyn of the city of New York, in the county of Kings, in the State of New York, have invented certain new and useful Improvements in Controlling Devices for Mechanical Musical Instruments, of which the following is a specification, reference being had to the accompanying drawings, which form a part hereof.

This invention relates to devices for controlling, at the will of the performer, the operation of pneumatically actuated musical instruments and has for its objects to provide improved devices for controlling the air connections between the motor for the music sheet and the main suction or main windway for the purpose of regulating what may be called the standard tempo of the composition to be rendered, to provide improved auxiliary tempo regulating devices whereby the tempo may be accelerated or retarded temporarily, at the will of the performer, with a return to the standard tempo, to provide improved devices whereby a direct connection, without the intervention of a governor, between the motor and the main windway may be effected for the purpose of accomplishing the reroll of the music sheet at high speed, to provide improved devices whereby the instrument shall be silenced through the cutting off of communication between the player pneumatics and the main windway during the reroll of the music sheet, and generally to improve the construction and operation of the various devices which are employed in the accomplishment of the several functions and operations above referred to.

The invention will be more fully explained hereinafter with reference to the accompanying drawings in which it is illustrated and in which—

Figure 1 is a view in front elevation, with the casing removed, of so much of a player piano as is necessary to enable the application of the invention thereto to be understood. Fig. 2 is a detail view, in front elevation and on a larger scale, of the motor controlling devices shown in Fig. 1. Fig. 3 is a top view of the devices shown in Fig. 2. Fig. 4 is a detail view, in section and on a larger scale, of the silencer valve shown in Fig. 1. Fig. 5 is a detail view, in section

and on a larger scale, of the rewind valve shown in Fig. 1. Fig. 6 is a detail view in front elevation showing the governor pneumatic and a portion of the windway with the ports through which connection with the controlling devices, etc. is effected. Fig. 7 is a detail view in vertical section, on the plane indicated by the line 7—7 of Fig. 6, looking in the direction of the arrows. Fig. 8 is a detail view of the same parts in horizontal section, the controlling devices being also shown. Fig. 9 is a detail view in elevation, of the main tempo valve shown in Figs. 1, 2, 3 and 8, the cylinder in which it is seated being shown in section. Fig. 10 is a similar view but in section on the plane at right angles to that of Fig. 9, the position of the bleed port being indicated by dotted lines. Fig. 11 is a detail view in section on the plane indicated by the line 11—11 of Fig. 9, looking in the direction of the arrows. Fig. 12 is a detail view in section on the plane indicated by the line 12—12 of Fig. 9, looking in the direction of the arrows. Fig. 13 is a detail view partly in section and partly in elevation of the auxiliary tempo valve shown in Figs. 1, 2, 3 and 8, with the cylinder in which it is seated. Fig. 14 is a detail view of the auxiliary tempo valve removed from its seat. Fig. 15 is a view in elevation of the parts shown in Fig. 13 as seen from the left.

In Fig. 1 of the drawings one embodiment of the invention is shown as applied to a player piano of usual construction, comprising a tracker box a , with its appurtenances, a pneumatic motor a' , a bank a^2 of player pneumatics with their valves, main bellows a^3 a^4 , equalizer bellows a^4 a^5 and operating pedals a^5 . The bellows are connected as usual with the windway b which in turn is connected at one end, through the silencing valve c , hereinafter described, and the duct c' with the common windway of the player pneumatics, and at the other end, through the controlling devices to be described and with which the invention is particularly concerned, and the duct b' with the motor a' .

The main or standard tempo regulating device comprises a cylindrical shell or casing d which has at d' a bleed port which communicates directly with the main channel b^2 of the windway b , and at d^2 a port which communicates, through a duct b^3 carried through the windway, and a duct b^4 with the pneumatic governor f hereinafter

- referred to, and at d^3 a port which communicates, through the duct d^4 , with the auxiliary tempo regulator, or accelerating and retarding device, hereinafter referred to.
- 5 Within the cylindrical shell d is mounted a cylindrical, tubular valve e which has a port e' for registration with the bleed port d' . The port e' is varied, as may be desired, by a sliding block e^2 which is carried by an adjusting screw e^3 , threaded in the cap e^4 of the valve e . The valve e is also provided, at e^5 , with a port which is adapted to register with the key-hole port d^3 above referred to. The position of the valve e is determined by manual adjustment through any suitable means, as by an arm e^7 secured to the stem e^6 of the valve and connected by a rod e^8 and suitable intermediate connections with the tempo regulating handle e^9 .
- 10 The duct d^4 is connected indirectly, as hereinafter described, to the motor and the speed of the motor, except as varied by the auxiliary tempo regulating device, is determined by the volume of air which is drawn through the duct d^4 and therefore by the extent to which the key-hole port d^3 is opened by rotary movement of the valve e . The air which is drawn through the port d^3 is drawn mainly from the interior of the hollow cylindrical valve e through the connection d^2 to the governor, so that the speed of the motor is determined by governed air and is not subject to varying degrees of vacuum within the main windway produced through changes in operation of the pedal.
- 15 The bleed port d' , which communicates directly with the main windway b^2 , permits a small amount of air to be drawn from the motor, which amount varies with the regulation of the tempo valve and may be carefully regulated by adjustment of the sliding block e^2 . Without such bleed hard pumping may cause the motor to stall through increase of pressure of the music sheet against the tracker bar and of various moving parts of the mechanism which are subjected to the air pressure against those parts in contact with which they move. The bleed, however, affords a direct communication between the motor and the main windway b^2 and therefore permits the greater vacuum which, at the time of hard pumping, exists in the windway b^2 and tends to stall the motor, to act directly, but under suitable regulation, upon the motor and therefore to overcome the tendency to stall or perhaps to slow down if it does not actually stall.
- 20 The governor f , with which the tempo regulating device d communicates through the port d^2 and channel $b^3 b^4$, is substantially of ordinary construction. It comprises an ordinary pneumatic which communicates with the channel $b^3 b^4$, is provided with an adjustable compensating spring f' , to regulate the speed of the motor through adjust-

ment of the governor, and communicates also with the main windway b^2 through a channel f^2 and a valve chamber f^3 , the movable member of the governor bellows carrying the cylindrical valve f^4 which, as the vacuum within the main windway b^2 increases, causing the governor bellows to collapse partly, moves over the mouth of the channel f^2 and thus reduces the vacuum within the bellows and in the usual manner prevents variation in the speed of the motor.

The standard tempo being determined and maintained through control of the speed of the motor in the manner already described, it becomes desirable to make it possible, at the will of the performer, to accelerate or retard temporarily the speed of the motor, as the proper performance of the composition may require, with a return to the normal or standard tempo. The auxiliary tempo controlling device, provided for this purpose, is therefore, by preference, arranged between the motor and the main tempo regulating device and to act upon the air which has already been regulated by the main tempo regulating device and in which the pressure has been made uniform by the governor. This auxiliary tempo regulating device or accelerating and retarding device, comprises a cylindrical shell or casing g which communicates with the main tempo device d through the duct d^4 above referred to, having a key-hole port g' for communication with such duct. It is provided also with a key-hole port g^2 for communication with the governor f , through a port b^5 and the channel $b^3 b^4$, as shown in Figs. 6 and 7, and is also provided with a key-hole port g^3 for communication with the motor through a channel g^4 and the duct b' .

Within the cylindrical shell g is mounted a cylindrical, hollow valve h which is provided with a port h' for registration with the port g' in the shell, with a port h^2 for registration with the port g^2 in the shell, and with a port h^3 for registration with the port g^3 in the shell. It will be understood that each of the ports $h' h^2 h^3$ of the valve h , as well as the port e^5 of the valve e , is divided by a narrow bridge for the sake of strength, but such bridges may be neglected so far as the operations of the valves are concerned.

The valve h is subject to manual control by the performer independently of the manual control of the main tempo valve e , but with provisions for returning it to its neutral or normal position when released by the performer. To this end the stem h^4 of the valve h is provided with a gear h^5 which is engaged by a gear h^6 . The latter is fixed to a short vertical shaft h^7 , which is mounted in suitable bearings and has secured thereto an arm h^8 . The latter is connected by a link h^9 and suitable intermediate con-

nections with an auxiliary tempo handle h^{10} . The arm h^8 carries a stud h^{11} which stands between two yielding stops h^{12} and h^{13} , which are carried by pivoted arms h^{14} and h^{15} . The arms h^{14} h^{15} are pulled normally toward each other by a spring h^{16} , their movement toward each other being limited by fixed stops h^{17} and h^{18} . It will be obvious that whenever the arm h^8 is moved by the handle h^{10} and the intermediate connections to one side or the other and is released it will return to its normal or neutral position and that the valve h in this manner will also be returned to its normal or neutral position and the speed of the motor, which has been accelerated or retarded with respect to the predetermined speed, will also be restored to that predetermined speed. It will be understood that the main tempo regulating valve e is shown in Figs. 9, 10, 11 and 12 in the position for zero speed of the motor, that is, with the port d^3 and the bleed port d^4 completely closed and thereby cutting off all suction from the motor, and that when the valve e is turned in a clockwise direction the port d^3 is opened gradually, thereby starting the motor and increasing its speed and that the bleed port d^4 is also opened gradually, whereby direct suction from the main windway is increased in proportion to the increase of speed of the motor, so that the power of the motor is increased with the tempo, as should be the case. It will also be understood that the auxiliary tempo valve h , as shown in Fig. 13 is in its normal or neutral position so that rotation of the valve h in a clockwise direction gradually closes the port g' and the port g^3 , thereby reducing the flow from the motor and retarding the tempo, while rotation of the valve h in an anti-clockwise direction, while permitting the ports g' and g^3 to remain open, by reason of the length of the ports h' and h^3 , gradually opens the port g^2 and thereby increases the flow from the motor to the governor and therefore accelerates the tempo.

As is desirable in controlling devices for mechanical musical instruments, provision is made in the present case whereby a direct connection is established between the motor and the main windway, in place of the indirect connection from the governor and tempo regulating devices, when the gears of the tracker box are shifted for the reroll of the music sheet. Such shifting of the gears may be effected in any usual or suitable manner, a handle i being shown as connected to a link i' , a rock shaft i^2 and a link i^3 to the lever i^4 by which the gear shifting or clutch shifting is directly effected. Advantage is taken of the movement of the lever i to initiate the operation of pneumatic devices for placing the motor in direct connection with the windway. The handle i

is provided with a finger i^5 which, in the operative movement of the handle i , opens a valve h and, through a duct h' and a T-coupling h^2 admits air to the lower end of a shell or valve chamber h^3 below a piston h^4 . ⁷⁰ A perforated partition h^5 within the valve chamber h^3 supports, normally, a valve h^6 , which closes the passage through the partition. The piston h^4 is connected with the valve h^6 by a rod h^7 , a spring h^8 , acting ⁷⁵ against the partition h^5 , serving to hold the valve h^6 normally down upon its seat. The portion of the valve chamber or casing below the partition h^5 is provided with a port h^9 which communicates directly with the main windway, as indicated by the dotted lines in Fig. 2, while the upper portion of the chamber or casing is provided with a port h^{10} which communicates with the motor through the channel g^4 , as clearly shown in ⁸⁰ Figs. 5 and 8. Normally, when the valve h is closed, the valve h^6 closes the openings through the partition h^5 and therefore cuts off direct communication between the motor and the main windway, but as soon as the ⁸⁵ valve h is opened, admitting atmospheric pressure to the under side of the piston h^4 , the suction of the main windway lifts the piston h^4 and with it the piston h^6 (which is of smaller diameter) and thereby establishes ⁹⁰ direct communication between the ports h^9 and h^{10} through the openings of the partition h^5 , and therefore direct communication between the motor and the main windway, ⁹⁵ whereby the motor is driven at high speed ¹⁰⁰ during the reroll. It is also desirable that during the reroll, and also at other times when it is desired to omit a portion of the music, to provide means for cutting off the player pneumatics from communication ¹⁰⁵ with the main windway. For this purpose there is provided a button m which is adapted, by pressure, to open a valve m' so as to admit atmospheric air to a duct m^2 which may form an extension of the duct h' . By ¹¹⁰ this means the operation of the pneumatic h^3 , to place the motor in direct connection with the main windway, so that the motor shall be driven at high speed, may be initiated at any time, without the operation ¹¹⁵ of the reroll devices. ¹²⁰
The operation of the silencing device, or the device for cutting off communication between the player pneumatics and the main windway, is initiated either by movement of the reroll lever i or by pressure on the silencing button m , atmospheric pressure being admitted from either valve h or m' through the duct h' , the T-coupling h^2 , and the duct c^2 , to the silencing device c . The latter, as shown in Fig. 4, is somewhat smaller in construction to the high speed, direct connection device h^3 . It comprises a cylindrical casing or valve chamber c^3 with a nipple c^4 for connection to the duct c^2 , a perforated ¹²⁵ ¹³⁰

partition c^5 , a nipple c^8 for connection with the duct c' which leads to the common windway of the pneumatic, and a port c^7 , above the perforated partition c^5 , communicating directly with the main windway. A piston c^8 , below the perforated partition c^5 , has a stem c^9 upon which is placed loosely, above the perforated partition c^5 , a valve c^{10} . The latter is held normally against the seat c^{11} , 10 to cut off communication between the main windway and the duct c' , by a light spring c^{12} which encircles the stem or rod c^9 and rests on a shoulder c^{13} . It is obvious that during ordinary playing the suction of the 15 main windway, acting through the port c^7 , will pull down the valve c^{10} from its seat and will act, through the duct c^4 , upon the player pneumatics as usual. When, however, either the valve k or the valve m' is 20 opened and atmospheric pressure is admitted to the under side of the valve c^8 , the suction of the main windway, acting through the perforated partition c^5 , will lift the piston c^8 and so hold the smaller valve c^{10} 25 firmly against its seat, cutting off communication between the windway and the player pneumatics.

The purpose of supporting the valve c^{10} 30 yieldingly on the light spiral spring c^{12} is to permit the valve to act as an equalizer. It is well known that in the operation of pneumatic piano players it frequently happens that the pulsations of the air current produced by the rapid repetition of a single 35 note can be felt by the performer through the pedals, generally to his annoyance and to the detriment of the musical effect. It is often found that the supporting of the valve c^{10} yieldingly, so that it flutters in response to the pulsations of the air current, 40 opening wider as each pulsation approaches its peak and thereby produces a practically uniform tension in the main windway, preventing the transmission of the pulsations 45 to the pedals.

The operation of each part of the improved devices has been sufficiently explained in connection with the description of the construction, and so far as the manipulation of the devices is concerned it will 50 be understood that the tempo lever e^9 is set to give the proper standard tempo for the composition to be performed and that the accelerando and rallentando effects are then 55 produced by movement of the auxiliary tempo lever h^{10} to the right for an accelerando effect and to the left for a rallentando effect, the lever returning to its neutral position as soon as released. If the music sheet 60 is to be rerolled the reroll lever i is thrown to the left and thereby the shifting of the gears in the tracker box is effected and at the same time the valve k is opened and, 65 through the pneumatic device k^3 , the motor is placed in direct connection with the main

windway and is thereby operated at high speed, the direct connection being cut off as soon as the reroll lever i is thrown to the right. At the same time that the pneumatic k^3 acts to establish the direct connection, 70 the pneumatic c acts to cut off communication between the main windway and the player pneumatics, thereby silencing the instrument, and at the same time when the pneumatic k^3 cuts off direct communication 75 between the motor and the main windway the pneumatic c restores connection between the main windway and the player pneumatics, thereby placing the instrument again in condition for playing. If at any time 80 it is desired to skip any portion of the music sheet, pressure on the button m causes the pneumatic c to cut off communication between the main windway and the player pneumatics and at the same time causes the 85 pneumatic k^3 to place the motor in direct communication with the main windway, so that the motor shall operate at high speed. As soon as pressure on the button m is released the instrument is again restored to 90 playing condition.

It will be understood that except so far as may be pointed out specifically in the claims the invention is not limited to the precise construction and arrangement of parts shown and described herein and that other forms of valves, pneumatics and other devices, well known in the art, might be substituted for those shown and described. 95

We claim as our invention:—

1. In a mechanical musical instrument, the combination of a motor, a main windway, a governing device and a tempo controlling valve, air ways being provided from the motor to the main wind-way through the tempo valve and the governor and from the motor to the main wind-way through the tempo valve direct to the main wind-way, whereby the motor is at the same time connected with the main windway through the governor and directly with the main wind-way through the tempo valve. 105

2. In a mechanical musical instrument, the combination of a motor, a main windway, a governing device and a tempo controlling valve, an air way being provided from the motor to the main wind-way through the tempo valve and the governor and the tempo valve having also a direct connection to the main wind-way. 110

3. In a mechanical musical instrument, the combination of a motor, a main windway, a governing device and a tempo controlling valve, the casing of the tempo valve having a port for connection to the motor, a port for connection to the main wind-way through the governor, and a port for direct connection to the main wind-way and the valve body of the tempo valve controlling both the connection from the governor to 115 120 125 130

- the motor and the direct connection to the main wind-way.
4. In a mechanical musical instrument, the combination of a motor, a main wind-way, a governing device and a tempo controlling valve, the casing of the tempo valve having a port for connection to the motor, a port for connection to the main wind-way through the governor, and a port for direct connection to the main wind-way and the valve body of the tempo valve controlling both the connection from the governor to the motor and the direct connection to the main wind-way, independent means being provided for regulating at will the flow of air through said direct connection.
5. In a mechanical musical instrument, the combination of a motor, a main wind-way, a governing device and a tempo controlling valve, the casing of the tempo valve having a port for connection to the motor, a port for connection to the main wind-way through the governor, and a port for direct connection to the main wind-way and the valve body of the tempo valve controlling both the connection from the governor to the motor and the direct connection to the main wind-way, the valve body being provided with a port for coaction with the port in the casing which communicates directly with the main wind-way, and being provided also with an adjustable block to vary the area of the last named port in the valve body.
- 35 6. In a mechanical musical instrument, the combination of a motor, a main wind-way, a governing device and a tempo controlling valve, said tempo controlling valve comprising a cylindrical shell having a port for communicating with the motor, a port for communication with the governor, and a port for direct communication with the main wind-way, and a cylindrical, tubular valve body having an opening for communication with the motor, a port for communication with the governor port and a port for communication with the direct port into the main wind-way.
7. In a mechanical musical instrument, the combination of a motor, a main wind-way, a governing device and a tempo controlling valve, said tempo controlling valve comprising a cylindrical shell having a port for communication with the motor, a port for communication with the governor, and a port for direct communication with the main wind-way, and a cylindrical, tubular valve body having an opening for communication with the motor, a port for communication with the governor port and a port for communication with the direct port into the main wind-way, the valve body being provided also with an adjustable block for varying the area of the last mentioned port therein.
8. In a mechanical musical instrument, the combination of a motor, a main wind-way, a governor having an air connection with the main wind-way and an air connection with the motor, a main tempo valve interposed in the connection between the governor and the motor, and an auxiliary tempo valve also interposed in the connection between the governor and the motor and in connection between the main tempo valve and the motor, whereby the air current between the motor and the governor is subjected to the combined control of the main tempo valve and the auxiliary tempo valve and to the independent control of the auxiliary tempo valve.
9. In a mechanical musical instrument, the combination of a motor, a main wind-way, a governor having an air connection with the main wind-way and an air connection with the motor, a main tempo valve comprising a casing having a port for connection to the governor and a port for connection to the hereinafter mentioned auxiliary tempo valve and a valve body for controlling the flow of air from one port to another, and an auxiliary tempo valve comprising a casing having a port for connection to the main tempo valve, a port for connection to the governor and a port for connection to the motor, and a valve body for controlling the flow of air through said ports.
10. In a mechanical musical instrument, the combination of a motor, a main wind-way, a governor having an air connection with the main wind-way and an air connection with the motor, a main tempo valve comprising a cylindrical casing having a port for connection to the governor and a port for connection to the auxiliary tempo valve hereinafter mentioned, and a rotary tubular valve body, having an opening for communication with the first mentioned port in the casing and a port for communication with the last mentioned port in the casing, and an auxiliary tempo valve comprising a cylindrical valve casing having a port for connection with the main tempo valve, a port for connection with the governor, and a port for connection with the motor, and a rotary valve body having ports for controlling the flow of air through the ports in the casing.
11. In a mechanical musical instrument, the combination of a main wind-way, a motor, a governor, an air connection from the main wind-way through the governor to the motor, a rotary tempo valve interposed in the connection between the governor and the motor, a pivoted arm and connections for operating the valve, and pivoted spring-pressed arms bearing oppositely against the first named arm to restore it to neutral position after displacement in either direction.

12. In a mechanical musical instrument, the combination of a main wind-way, a motor, a governor, an air connection from the main wind-way through the governor to the motor, a rotary tempo valve interposed in the connection between the governor and the motor, a pivoted arm and intermediate gearing for operating the valve, and spring-pressed arms bearing oppositely against the

first named arm to restore it to neutral position after displacement in either direction.

This specification signed and witnessed this 29th day of March, A. D. 1915.
